UNITED STATES PATENT OFFICE.

ROBERT CECCHINI, OF SPRINGFIELD, MASSACHUSETTS, ASSIGNOR, BY DIRECT AND MESNE ASSIGNMENTS, OF ONE-FOURTH TO ARCHIE BEDROSSIAN, ONE-FOURTH TO ARCHIE GIRAGOSIAN, AND ONE-FOURTH TO EUGENE ARITI, ALL OF SPRINGFIELD, MASSACHUSETTS.

RAILWAY-TRAIN STOP.

1,118,890.

Specification of Letters Patent.

Patented Nov. 24, 1914.

Application filed October 25, 1913. Serial No. 797,183.

To all whom it may concern:

Be it known that I, ROBERT CECCHINI, a British subject, and resident of Springfield, in the county of Hampden and State 5 of Massachusetts, have invented certain new and useful Improvements in Railway-Train Stops, of which the following is a full, clear, and exact description.

This invention relates to means for the 10 stopping of a railway train in case of a signal being set for danger on the part of the engineer, by neglect or carelessness, running beyond the signal.

The present apparatus is one operative 15 when the signal is set at danger for automatically shutting the throttle valve of the locomotive and for then operating the "engineer's valve" for setting the air brakes necessary.

20 The invention comprises a vertically movable rail located along the trackway and having connection with the danger signal whereby when such signal is set the rail will be elevated, an electric motor mounted on 25 the locomotive and coacting, through suitable means or connections with the throttle valve and with the air brake valve, so that when said motor is run said valves will be operated, a normally open electric circuit 30 including a generator and in which said motor is connected, a movable circuit closing member, and a device carried by and movable on the locomotive adapted to have impingement against, and to be moved by 35 said vertically movable rail, while the latter is in its elevated position for moving the circuit closing member to position for establishing the current through, and for causing the running of, the electric motor.

40 The invention is described in conjunction with the accompanying drawings and is set forth in the claim.

In the drawings:—Figure 1 is a side elevation showing a portion of the trackway, a 45 vertically movable rail and parts on the locomotive. Fig. 2 is a view showing parts included in Fig. 1 as at right angles thereto and showing connections between the danger signal and the vertically movable rail section. Fig. 3 is a sectional elevation of the 50 rail section, the circuit closing means on a locomotive controlled by the position

thereof and appurtenances of the circuit closing devices. Fig. 4 is a diagrammatic view hereinafter referred to. Fig. 5 is a 55 plan view. Fig. 6 is an elevation showing the motor and the means operated thereby and coacting with the locomotive throttle valve and the air brake valve for the actuations thereof.

60 Similar characters of reference indicate corresponding parts in all of the views.

In the drawings, A represents the railroad track alongside which is a movable signal B, here represented in the form of a 65 swinging semaphore with lamps a (red, white and green) for night use. The semaphore is indicated by full lines in safety position,—its danger position being represented by dotted lines. An extension of the 70 semaphore constitutes a support for the lamps a; and this signal is understood as an exemplification of a usual form of signal to be included in a block signal system, and to be operated as usually heretofore known. 75

D represents a comparatively short and light rail section having inclined ends arranged alongside one or the other of the tracks and adjacent the signal, and it is carried on pivoted lever-like arms b b, one at least of 80 which is made as a bell crank with which a flexible connection d is secured, the same being properly sheave guided as indicated at d² is also secured to the signal, so that when under the setting means for the signal 85 the latter is maintained in the danger position, the short rail section D will be elevated in a sufficient extent as indicated by the dotted lines in Figs. 1 and 2.

F represents portions of the locomotive 90 on which mechanisms and devices herein-after referred to are provided.

f represents the throttle valve stem, f² being the operating lever therefor, and G represents the "engineer's valve" controlling 95 the air brake, g indicating its operating handle.

J represents an electric motor understood as being in or near the cab of the locomotive and having on its shaft the gear wheel or 100 pinion h. This pinion is in mesh with a rack bar i, a rodlike extension i² of which has connection indirectly with the throttle lever f², that is it is connected with the

throttle latch device j^3 so that when the rack bar is moved, it will be effective to first unlatch the latter and then to cause a swinging thereof for closing the throttle valve. 5 Adjacent and parallel with the rack bar extension i^2 is another bar j supported and slideable in and through suitable supports or brackets j' therefor and having a shoulder or abutment j^3 thereon. The rack bar extension i^2 carries a rigidly affixed arm i^3 provided with a tubular boss i^4 at its extremity which plays sleeve-like relatively to the bar j . The angular extension j^2 of the bar j is extended into proximity with the operating handle g of the engineer's valve and it has a connection therewith.

When the motor J is run, by the establishment of a current through the circuit therefor, it causes the endwise movement of 20 the rack bar for the closing of the throttle valve, shutting off the steam employed for the driving of the locomotive and thereafter the operation of the engineer's valve for the setting of the air brake.

25 It is to be noticed that the abutment i^4 will be carried in unison with the rack bar for a considerable distance before it strikes the abutment j^3 for moving the bar j which operatively coacts with the air brake valve.

30 The pinion h may be on a shaft section separate from the main shaft of the electric motor and connected thereto by a friction clutch k so that in an emergency requiring the operation of this apparatus notwithstanding the motor may continue to run for some time after the valves have been operated, such running of the motor will be ineffective for any injurious result to the devices in combination therewith.

35 40 n represent conductors constituting a normally open circuit for the motor J , the same having connected therein a battery or generator o and the terminals of the wires n are electrically connected with separated contact pieces m located within a casing L carried at a lower portion of the locomotive.

45 q represents a block to act as a circuit closure when moved to contact against both of the said contact pieces m . This block q normally rests in its lowered position supported by the bottom of the casing, and it has a depending stem r .

50 55 s represents an approximately horizontal lever-like member pivotally mounted in a bracket t at one end thereof and having a stud and slot connection at its other end with the depending stem of the circuit closing block q . This lever intermediately thereof in a depending yoke extension s^2 carries a roller u which when the vertically movable rail D is elevated simultaneously with the setting of the signal at "danger," will impinge against the rail section and be upwardly forced to elevate the circuit clos-

ing member q , causing the starting of the motor and the actuation of the train stopping valve. The ends of the circuit closing block q are beveled, and adjacent such bevel ends are duplicated spring pressed bevel edged locks or latches v slidably mounted in guides therefor in the casing so that when the circuit closing block is forced upwardly to strike against the contacts m it will be held in its raised position and for holding the circuit closed until purposely released by the engineer.

55 60 As a means for the disconnection of the latches v so that the block q may descend by its own weight or as forced by the springs w to its lowered normal position, sheave guided cords x are connected with the latches and with a common rod y which is pivotally jointed to an operating lever z understood as having a location on the locomotive in any conveniently accessible position.

65 70 The contacts or terminals m are represented as being carried by a vertically movable insulated body m^2 held on the ledge-like portion m^3 of the casing by the springs m^4 so that any violent upward movement of the circuit closing block q will be but yieldingly resisted by the downwardly spring pressed terminal contacts m .

75 80 Of course, as manifest, the apparatus in which the present invention is comprised, may at pleasure be utilized for automatically controlling either the steam throttle valve or the air brake valve, but for the double assurance it is preferable to utilize the apparatus for the automatic controlling of both the throttle valve and the engineer's or air brake valve; and instead of having the arrangement such that the air brake valve will not be operated until the throttle valve has been moved more or less toward its closed position, the arm i^3 may be so adjusted on the rack bar extension i^2 as to have little or no lost motion relatively to the abutment j^3 on the air brake valve operating bar j .

85 I claim:—

90 In a railway train stop, in combination, the trackway, a vertically movable rail located along the trackway and means for causing the elevation thereof, a locomotive having a controlling valve, an electric motor mounted on the locomotive and coacting with said controlling valve, a normally open circuit including a generator and having a pair of terminal contact members, a casing in which said contact members are supported, a lever arm carried by the locomotive and having a roller adapted for impingement against said vertically movable rail, upon the elevation of the latter, a block to which said roller carrying lever is connected, having a portion adapted for a circuit closing engagement against said con-

taets and having opposite edges thereof beveled, spring pressed bevel edged latches slidably mounted in said casing and with which said block coacts, sheave guided 5 cords connected to the said latches, and an operating member to which said cords are connected.

Signed by me at Springfield, Mass., in presence of two subscribing witnesses.

ROBERT CECCHINI.
